UNITED STATES PATENT OFFICE.

THOMAS DANQUARD, OF NEW YORK, N. Y., ASSIGNOR TO AUTOPIANO COMPANY, OF NEW YORK, N. Y., A CORPORATION OF NEW YORK.

FOLDING PEDAL.

No. 884,643.

Specification of Letters Patent.

Patented April 14, 1908.

Continuation of application Serial No. 274,920, filed August 19, 1905. This application filed April 22, 1907. Serial No. 369,517.

To all whom it may concern:

Be it known that I, THOMAS DANQUARD, a citizen of the United States, residing at New York, in the county of New York and State of New York, have invented a new and useful Folding Pedal, of which the following is a specification.

This is a continuation of my application for patent on the same subject, Serial Number 274,920 filed August 19, 1905.

The object of this invention is to provide a new and improved folding pedal construction especially adapted for use in connection with piano or organ cases wherein it is desired to fold the pedals into the case to get them out of the way.

The principal aim of the invention is to provide a strong, simple and effective device for this purpose.

The invention is illustrated in the accompanying two sheets of drawings referring to which,

Figure 1 is a sectional elevation of one form of the apparatus. Fig. 2 is a plan view 25 of the parts making up the folding pedal construction. Fig. 3 is a view similar to Fig. 1 illustrating the pedals folded into the case. Fig. 4 is a view similar to Fig. 1 illustrating another form in which the invention is preferably embodied, and Fig. 5 is a similar view showing the parts in a different position.

Referring to the drawings and in detail A designates the case which is provided with an opening 10 at its front side which opening 35 may be closed by any of the usual doors or other devices when the pedals are not in use.

The lower rail is designated by 11. A brace or winding box extends crosswise of the case. The rigid leaves 13 of the bellows 40 are secured to said brace 12 and to brackets 14, and the movable leaves or numbers 15 of the bellows are pivoted to the top of the rigid leaves.

Operating connections extend from the 45 movable leaves. These operating connections in the arrangement shown in the first three figures, consist of brackets 16 rigidly secured to the movable leaves and extending arms 17-17 rigidly connected to said brackets.

18 designates the pedal support which may have small feet provided with rubber cushions.

The pedals P--P are hinged or pivoted to 55 this support. The pedals P--P are con-

nected by pitmen 19-19 to the arms 17-17, the pitmen being pivoted both to the pedals and to said arms.

Secured to the pedal support 18 are braces 20-20. These braces are rigidly secured to the pedal support 18 and are pivoted to blocks 21-21 arranged behind the lower rail 11. The braces 20-20 are bent so as to fit closely to the lower rail 11, as shown in Fig. 1, when the pedals are in operative position.

It will be noticed that the pivots of the braces 20-20 come below the pivots of the pitmen 19-19 inside of the case. By this construction the pedals can be folded back into the case and the pitmen and braces constrain the movements of the pedals so that the upper ends thereof will swing around under the brace or box 12, as shown in Fig. 3. By this arrangement, the pedals can be kept as low as possible when folded back into the case and the lower rail does not have to be mutilated or cut in any way. In this way a strong, simple and efficient device for the purpose stated is provided.

In some cases the invention may be practiced in this way but instead of using the rigid brackets and arms 17, I prefer to use links 170 loosely pivoted to the movable leaves 15-15 of the bellows to allow side-wise movement and additionally connect said pivoted links 170 to a stationary part by swinging links 171, as shown in Figs. 4 and 5. These links are pivotally suspended from a stationary part of the pump, as the wind chest. The lower ends are turned toward 90 the center thus forming a strong and durable fulcrum pin from the two pedal arms. The links 170 are slipped on the inturned ends of the links 171. This construction gives a toggle movement to the movable leaves 95 when the bellows are operated, which is desired for some uses, as it increases the leverage by controlling the position of the pivot between the links 170 and 19. In this case also a single bracket 140 is used for supporting the leaf 13 and the brace 20. This bracket extends substantially to the rear of the lower rail for this purpose. It terminates below the top of the rail.

The arrangements herein shown and described may be varied by a skilled mechanic without departing from the scope of my invention as expressed in the claims.

Having thus fully described my invention, what I claim is:—

1. The combination of a case for a music playing device having a lower rail, a support, 5
pedals connected with said support, pitmen pivoted to the pedals to operate connections
inside the case, and braces connected with
said support and pivoted inside the case at
points below the pivots of the pitmen and
below the top of the lower rail, said braces
being so formed as to extend partly around
the lower rail when the pedals are in opera- 10
tive position.
2. The combination with a case for a mu-
sical instrument having a lower rail, of a sup-
port, pedals pivoted to the support, pitmen
pivoted to said pedals, operating connections
inside the case to which said pitmen are
pivoted, braces connected to said support and
pivoted inside the case, said braces being
bent so as to extend partly around the lower
rail when the pedals are in operative position
and to fold into the case when the pedals are
folded into inoperative position. 15
3. The combination with a case having a
lower rail a wind box arranged therein, bel-
lows secured to said wind box, a support,
pedals pivoted to the support, pitmen pivoted
to said pedals, operating connections 20
extending from said bellows and pivoted to
the pitmen, and braces connected with said
support and pivoted inside the case behind
said lower rail and near the bottom thereof. 25
4. The combination with a case for a mu-
sical instrument having a lower rail, of brack-
ets at the bottom of the case and extending
substantially to the rear of the rail and be- 30
- low its top, a movable member connected
with said brackets, links connected with the
movable member, pedals connected with the
links, and braces pivoted to the forward ends
of the brackets and pivotally connected with 35
the pedals, said braces extending over the
lower rail. 40
5. The combination with a case having a
lower rail, of a wind box arranged therein,
bellows secured to said wind box, a support, 45
pedals pivoted thereto, pitmen pivoted to
said pedals, operating connections extending
from said bellows and pivoted to the pitmen,
and braces connected to said support and
pivoted inside the case behind said lower rail 50
and near the bottom thereof, said operating
connections comprising links pivoted to the
movable leaves of the bellows and swinging
links for supporting the fore ends of the first
named links and having inwardly turned 55
ends to which said links are pivoted.
6. In a pedal construction, the combina-
tion of a movable member, a pedal, a pitman
pivoted to the pedal, a link pivoted to the
movable member and to the pitman, and a 60
swinging link pivotally connected with the
pitman at the point at which said pitman is
pivoted to said first named link.

In testimony whereof I have hereunto set
my hand, in the presence of two subscribing 65
witnesses.
